DESIGN FOR A PARKING METER HOUSING

Paul F. Simpson, Washington, Conn., assignor to
International Meters, Inc., New York, N. Y., a
corporation of New York

Application December 2, 1947, Serial No. 142,927

Term of patent 14 years

(Cl. D52—3)

To all whom it may concern:

Be it known that I, Paul F. Simpson, a citizen of the United States, residing at Washington, Litchfield County, Connecticut, have invented a new, original, and ornamental Design for Parking Meter Housing, of which the following is a specification, reference being had to the accompanying drawing, forming a part thereof.

Fig. 1 of the drawing is a perspective view of a parking meter housing showing my new design and including the front or coin entrance side of the meter housing; and,

Fig. 2 is a similar view, including the rear of the meter housing.

I claim:

The ornamental design for a parking meter housing, as shown.

PAUL F. SIMPSON.
